UNITED STATES PATENT OFFICE

ALEXANDER J. DALLAS, OF U. S. ARMY, ASSIGNOR TO ALEXANDER M. KENADAY, SECRETARY OF THE NATIONAL ASSOCIATION OF VETERANS OF THE MEXICAN WAR, OF WASHINGTON, DISTRICT OF COLUMBIA.

DESIGN FOR A BADGE.

Specification forming part of Design No. 9,129, dated March 7, 1876; application filed February 23, 1876.
 [Term of Patent 7 years.]

To all whom it may concern:

Be it known that I, ALEXANDER JAMES DALLAS, major Twenty-third Infantry, of Omaha Barracks, in the county of Douglas and State of Nebraska, have originated a Design for Badges and other similar articles of manufacture; and I do hereby declare that the following is a full, clear, and exact description thereof, reference being had to the accompanying drawings, and to the letters of reference marked thereon, which form a part of this specification.

The nature of my design will be fully understood by reference to the accompanying drawings, and to the letters of reference marked thereon, in which—

A represents a clasp or bar having a border, *a*, inclosing the words "National Association Veterans;" B, a ribbon or connecting-piece, provided with vertical stripes *b* *b*¹ *b*², the stripe *b* being blue, the stripe *b*¹ white, and the stripe *b*² red, by preference. The arrangement of the colors of the stripes is not, however, an essential element of this design. C represents a shield, the outer edge of which is provided with a border, *c*, having the names of battles of the Mexican war thereon. At one corner of the shield C is a vessel, and at the opposite corner a cannon, while in the upper end of the shield is a bursting shell, beneath which is arranged a group of arms. About the center of the shield are arranged the word

"Mexico," a maguey plant surrounded by cactus, a castle, and the figures "1846," surrounded by a wreath, banded together below by a series of folds bearing the names of officers. Surrounding the wreath are arranged a series of stars.

The parts A and C may be formed of metal, and the connecting-piece B of silk or other fabric, or the whole design may be executed on metal, fabric, or other material.

What I claim as my invention is—

1. The design for a badge or similar article, composed of the shield C, having upon its face the representations of a ship, shell, group of arms, cannon, plants, castle, wreath, stars, and inclosing border *c*, substantially as described and shown.

2. The design for a badge or similar article, composed of the clasp or bar A, connecting-piece B, and shield C, having upon its face the emblematical representations, substantially as described, and shown in the accompanying drawing.

In testimony that I claim the foregoing as my own I herewith affix my signature in presence of two witnesses.

ALEXANDER JAMES DALLAS,
Major Twenty-third Infantry.
